MATERIAL HOLDING AND DUMPING CONTAINER

Howard F. Chapman, Jr., Dunkirk, Ohio

Application June 9, 1955, Serial No. 514,310

2 Claims. (Cl. 214—317)

My invention relates to material handling and particularly to equipment usable in a material pick-up, carry and dump system utilizing a well-known general purpose fork lift truck.

The invention has for its broadest object to provide a portable material holding container adapted for seizure and carry by a conventional fork lift truck and means, including an element on the container, enabling the fork lift truck to tilt the container and thereby dump it at a desired place.

My invention deals basically with the problem of extending the utility of a conventional fork lift truck. This is important to users who, by reason of limited funds or infrequent occasion of need, cannot afford or do not have special purpose equipment. In a sense, my invention enables the conventional fork lift truck to be applied to the tasks usually reserved to such special equipment as the revolving fork truck and other specially designed trucks.

My invention not only contemplates the provision of means enabling a conventional fork lift truck to tilt a container, as heretofore stated, but also the invention contemplates that such means shall enable the truck to recover the container in an orderly erect position, after tilting. This is important if the container is to be partially dumped at one dumping place and is then moved either to another dumping place for distributed dumping or to a refilling station, as in mixing. Also, if the sequence of material flow carried on in the container is to be a smooth and hence an efficient sequence, the recovery of the container, in an orderly manner and erect position, after dumping, is highly desirable.

A further object of my invention is to provide a dumpable container usable with conventional fork lift truck equipment in which the manipulation not only during the pick-up and carry stages but also in the dumping stage is entirely done without human intervention except in the operation of the fork lift truck. This enables dumping to be accomplished with a minimum of manpower and, hence, at a low cost.

Another object of my invention is to provide, in one of its embodiments, a cage having an element of the aforementioned tilt enabling means mounted thereon and into which a conventional material container sometimes hereinafter called a "primary" container may be placed for carrying and dumping. In accomplishing this object, my invention enables a user to obtain all the principal advantages of my invention in a material carrying and dumping operation from a plurality of conventional material containers instead of being obliged to provide a plurality of specially adapted containers each having an element of such tilt enabling means mounted thereon.

Still another and more particular object of my invention is to provide a material holding and dumping container of wide adaptability, low in its cost of construction, of practically no needed maintenance and of such simplicity that no more than the skill of a fork truck operator is needed to operate it.

My invention has for further objects to provide other advantageous structures and arrangements which will appear from the following description and an examination of the accompanying drawing. Structures embodying my invention may take various forms. I have selected a material handling and dumping container which constitutes

2

a specific embodiment of my invention and shall describe the same hereinafter, since such now appear to me as the best mode of carrying out my invention. Reference to the accompanying drawing has been had to facilitate such description. In making such description or using the accompanying drawing for reference, I do not imply, however, that variations from the chosen structures, which do in fact embody my invention manifest herein, are beyond the contemplation of my invention.

Figure 1 of the accompanying drawing illustrates a perspective view of a material holding container embodying my invention and having the features thereof. Figure 2 illustrates a view in elevation of the front of the container shown in Figure 1. Figure 3 is a diagrammatic illustration of a flow of operation, showing the use of the container of Figures 1 and 2, in conjunction with a conventional fork lift truck, moving through a sequence of (a) pick-up (b) carry and (c) (d) (e) dumping.

A material holding container which embodies my invention has, as an essential, means for pivotally engaging any of a multiple of horizontally extending struts, such as those which cap or extend along and comb the upper edge of a bin wall, a truck box, a tank or another container. In other details, such as the provisions for seizing the container, the provision for carrying the container and the provision for loading the container, the container may vary within a wide range of conventional structures.

I have chosen a container more like a cage into which a primary container of material may be placed as for the purpose of carry and dumping. It is not my intention, however, that this selection should overlock nor imply that I disclaim the adaptation of my invention directly to the primary container itself.

Referring to the accompanying drawing, it will be seen that I have selected a container 10 having side walls 11 and 12, front wall 14, bottom wall 15 and top wall 16, all in a box-like angular relation. One side of the container 10 is left open to provide a loading opening 17 through which a drum-like primary container 18 containing material, like that indicated at 19, or empty after dumping may be passed. Thus, the container 10 forms a cage or adapter by which conventional primary containers, such as the drum 18 or well-known tote boxes, dipping baskets and the like, may be handled in a dumping system.

In order that a conventional fork lift truck, such as the one indicated diagrammatically at 20, may engage the container 10 to lift and carry it from place to place, I provide horizontally extending flanges 21 on the exterior of each of the side walls 11 and 12. As shown in the accompanying drawing, each flange 21 may be formed from a length of angle iron extending across and suitably welded to its respective side wall and providing a ledge under which an arm 22 of the fork lift truck 20 may raise to engage and thus lift and carry the container 10, as shown at (a) and (b) in Figure 3 of the accompanying drawing. Preferably, the flanges 21 extend along horizontal lines just above the center of mass of the container 10.

Essential to the dumping operation is the provision on the container 10 of an element by which the container may pivotally engage, at the dumping station, with an upper edge, a dumping bin wall, the rim of receiving truck box or the rim of a tank or other container, such as is diagrammatically illustrated at 24 in Figure 3 of the accompanying drawing. Where the dumping station does not comprise such enclosing structure, a horizontally extending rigidly supported strut or back board, like the edge 25 indicated on the bin 24, is provided at the dumping station.

The aforesaid pivotally engageable element on the container may take various forms but a desirable form is one having the capacity to effect pivotal engagement with

edge 25 with a degree of automaticity and in response solely to the manipulation of the container 10 by the fork arms 22 of the truck 20. Additionally, it is desirable that said element have such form as to enable disengagement of said edge 25 again entirely through manipulation of the container 10 by the truck. By this provision, the operator of the truck 20 is enabled to effect the entire operation of container pick-up, carry, dump (shown in the sequence of Figure 3 of the accompanying drawing) erection and recovery, return and replace (the reverse sequence of that shown in Figure 3) without aid or assistance of a helper.

I find that the best form of such element is that of a pair of spaced hooks 30. The hooks 30 are each formed at the outer ends of a bar 31 suitably fixed, as by welding, to side walls 11 and 12 of the container 10 in a forwardly projecting relation from the container front wall 14. The disposition of the bars 31 relative to the center of mass of the container 10 is such as to locate the hooks 30 above a horizontal line passing through said center of mass and on one side of a vertical line passing through the center of mass. Each hook 30 has a leg 32 extending downwardly with respect to the container 10 and spaced from the container wall 14 a distance greater than the width of the edge 25. The leg 32 in its spaced relation to the wall 14 thus forms the hook mouth 33. Thus, when the container 10 is in a raised position, as shown at (b) in Figure 3, it may advance to a position locating the mouths 33 of the hooks 30 above and in vertical registration with the edge 25. Now when the container 10 is lowered, as shown in position (c) of Figure 3, the hooks 30 engage and will extend over and somewhat around the bin edges 25. This relation of the hooks 30 with regard to the edge 25 is sufficient to support the container 10 and its encaged primary container 18 in an elevated position, as shown at (d) in Figure 3 of the drawing.

This is the position at which the container 10 is disposed for tilting to dump. The fork arms 22 of the truck 20 are manipulated to disengage the container flanges 21. Tilting of the container 10 now may be effected by directing the fork arms 22 to engage the container 10 at a point on that side of a vertically extending line passing through the center of mass of the container 10 opposite to the side on which the hooks 30 are disposed and exerting an upward force of limited duration at such point. This causes the container 10 to pivot on the hooks 30 and about an axis coincident with the edge 25, dumping the contents 19 of the container 10 or 18 over the edge 25 into the dumping place 24. This is shown being done at (e) in Figure 3 of the accompanying drawing.

If desired, for tilting the container 10 to dump, the operator of the truck 20 may cause the fork arms to engage only at points of the flanges 21 which are on the opposite side of a vertical line passing through the container's center of mass to that on which the hooks 30 are disposed. Or the container 10 may be provided, as I have shown, with a pair of tilting journals 35 which provide purchase points engageable by the fork arms 22 of the truck in the dumping operation.

Each journal 35 consists preferably in a stub shaft suitably fixed to and extending outwardly from opposite side walls 11 and 12 of the container. The journals 35 are positioned relative to the center of mass of the container preferably well below and well to one side of the mentioned horizontal and vertical lines passing through such center of mass. This enables the operator of the truck 20 to exercise rather delicate control over the tilting and dumping operation notwithstanding the overall unwieldiness of the truck 20 itself.

Thus, as the container 10 is tilted, as shown at (e) in Figure 3, the material 19 pours through an opening 36 in the container 10 formed as by cutting away a portion of the top wall 16. The uncut portion of the wall 16 serves to retain the drum 18 from leaving the container 10 during dumping.

To recover the container 10 from its tilted dumping position, the truck operator lowers the fork arms 22. This allows the container 10 to again become erect and, as shown at (d) in Figure 3, suspended from the edge 25 of the bin 24. The arms 22 are now manipulated under the flanges 21, the container is raised disengaging the hooks 30, and may then be returned for reloading at its starting place.

Perhaps, it should be marked that, in the event it becomes desirable to use the container 10 as a primary container to be itself filled with material 19, the mentioned open side 17 of the container 10 will, of course, be closed by a suitable wall just as wall 14 closes the side of the container 10 opposite to the open side 17.

15 Thus, I provide a material holding and dumping container of considerable adaptability and simplicity, cheap in its initial cost, easily maintained and requiring minimal manpower in its use.

I claim:

20 1. A material holding and dumping container for use in a material dumping system including a fork lift truck and a horizontally extending rigid strut above a material dumping place, said container having a pair of rigid flange bars affixed to opposite sides of the container as to extend outwardly therefrom in a horizontal plane above the center of mass of the container and providing means adapted for engagement by a fork lift truck to lift and carry the container; a second pair of bars having downwardly extending end legs and affixed to said opposite sides and above the center of mass of the container and said flange bars so as to locate said end legs extending in the same direction relative to the container and in spaced relation to a container side intermediate and adjoining said opposite sides whereby the end legs and intermediate container side form coaxial and axially spaced inverted U-shaped hooks having their open mouths facing downwardly and adapted to engage a horizontally extending rigid strut above a material dumping place to thus pivotally support the container above said dumping place; and a pair of stub shafts affixed to the said opposite sides of the container as to extend axially and horizontally outward from coaxial points on said opposite sides of the container below the center of mass of said container and remote from said intermediate side of said container and providing journal means pivotally engageable by said fork lift truck, after the hook forming ends of the second pair of bars have engaged said strut above the material dumping place, to enable said truck by thrusting upwardly on said stub shafts to tilt the container over and about the points of engagement of the second bars hook forming ends and to thereby dump the container contents.

2. A material holding and dumping container as described in claim 1 in which the container has opposite side walls, a front wall intermediate and adjoining said side walls, and top and bottom walls in box-like angular relation to each other providing an open back sided cage for receiving and holding a conventional material holder therewithin; said top wall having an opening therein at a point which will be in registry with an open upper end of said conventional material holder when the same is placed in said container whereby the contents of said conventional material holder may pass through said top wall opening when the container is tilted, as aforesaid, and the material holder will be retained in the container during said tilting by the closed portion of said container top wall around said opening.
